UNITED STATES PATENT OFFICE.

GEORGE E. PRENTICE, OF NEW BRITAIN, CONNECTICUT.

PROCESS OF MAKING SNAP-FASTENERS.

1,214,481.

Specification of Letters Patent. Patented Jan. 30, 1917.

Application filed October 29, 1915. Serial No. 58,572.

To all whom it may concern:

Be it known that I, GEORGE E. PRENTICE, a citizen of the United States, residing at New Britain, in the county of Hartford and 5 State of Connecticut, have invented certain new and useful Improvements in Processes of Making Snap-Fasteners, of which the following is a specification.

My invention relates to improvements in 10 processes of making snap fasteners, and the object of my improvement is simplicity and economy in construction and convenience and efficiency in use.

In the accompanying drawing, Figure 1 15 is a plan view, considerably enlarged, showing my improved snap fastener. Fig. 2 is a bottom view of the same. Fig. 3 is a side elevation of the same. Fig. 4 is a plan view of the socket member only. Fig. 5 is a sectional view on the line $\alpha - \alpha$ of Fig. 1. Fig. 6 is a plan view of the blank for the securing plate for the socket member, in the condition previous to having the edge turned inwardly for being secured to the wire body 20 portion of the socket member. Fig. 7 is a side elevation of the same. Fig. 8 is a plan view of a modification of the socket member made of sheet metal. Fig. 9 is a sectional view on the line $y - y$ of Fig. 8, the 25 form for the blank being indicated by broken lines. Fig. 10 is a plan view of the blank for the socket member shown in Figs. 8 and 9. Figs. 11, 12, and 13 are views corresponding to Figs. 8, 9, and 10, showing 30 another modification of the socket member, also made of sheet metal. Fig. 14 is a sectional view, on an enlarged scale, on the line $z - z$ of Fig. 13, the form of the finished socket member being indicated by broken 35 lines.

My improved snap-fastener comprises a ball member and a socket member. The said ball member has a flat body portion 10 provided with openings 11 for the thread 40 by which the same is secured to one portion of a garment, and a ball 12 at the middle portion thereof and connected therewith by means of a neck 13. The ball 12 and neck 13 are generally of ordinary form and have 45 the usual curved form of contour, except that the neck 13 is shorter than usually found in snap-fasteners of the same class as that in which my improved device is 50 found.

The socket member comprises a body portion formed of wire and a securing plate

14 for holding the same in the particular form desired. The said body portion comprises a plurality of radially positioned loops 15, all in one plane, the openings 16 60 inclosed by the apex portions of the loops 15 and the body portions of the arms thereof serving as openings for receiving the stitches for securing the socket member to the garment. 65

The end portions 17 of the arms of the loops 15 are connected to the corresponding end portions of the adjacent loops, preferably by a return bend of the wire, as shown, the connecting portions or bends 18 uniting 70 to form the border wall for the ball receiving opening 19 at the middle of the socket member, and which opening is a good fit for the neck 13 of the ball 12.

Furthermore, the wire of which the body portion of the socket member is formed is of circular cross-section and of a size to correspond closely to the curvature of the opposed wall at the junction of the neck 13 and ball 12. Thus sharp corners are avoided 75 in the engaging parts of the socket member and ball member and long life of these parts is insured. 80

The ends 20 of the wire preferably meet 85 to form the apex portion of one of the loops 15.

The wire body portion of the socket member as described constitutes the active portion of the said socket member, the wire being sufficiently resilient to give way and permit the ball 12 to be entered through the middle opening 19 and when the connecting portions 18 have cleared the ball 12 to spring the said connecting portion 18 back 90 into engaging position against the neck 13. 95

In order to hold the parts of the wire body portion in the normal position I provide some form of securing means, such as the securing plate 14, of annular form. 100 The said securing plate engages with the apex portions of the loops 15, being previous to assembly of cup form, comprising the annular base plate 21, and the cylindrical upturned peripheral rim or edge 22. 105 The wire body portion is placed on the base plate 21 and the free edge portion 23 of the rim 22 is turned over on the outer face thereof, thus forming a reliable mechanical connection for the parts. 110

In the sheet metal form shown in Figs. 8, 9 and 10 the socket member consists of a single piece of sheet material of disk-like

form, having a complete circular peripheral edge. The same comprises the ball receiving hole 19^a at the middle, a plurality of angularly spaced stitching receiving holes 16^a in the body portion, and radial slits 24 connecting the holes 16^a and opening 19^a. Thus there are formed between the slits 24 a plurality of arms 25, extending inwardly from the peripheral portion, and which co-operate as spring arms to form a yielding socket for co-operating with the ball 12 and neck 13.

In order to provide proper resiliency of the sheet material and to provide also a rounded form of edge for both the stitch receiving holes 16^a and the middle opening 19^a, substantially like that provided for the wire form of structure described, I form the sheet material socket member from a blank of appreciably greater thickness than that of the finished article, as indicated in Fig. 10, the holes 16^a and opening 19^a in the blank being of course correspondingly larger in the blank. The blank as described is compressed a predetermined amount by a flat die, the edge portions assuming a bulging or rounded formation as shown in Fig. 9.

It is understood that the blank is formed by punching by means of dies, which operation results in forming a generally straight edge, with sharp corners, the edge being essentially a raw or rough edge and the corners being liable to cut a thread or to wear away if used to any appreciable extent as a bearing edge.

The compression process described serves to produce a finished effect to the edge, that is smooth and hard, and suitable for use as a bearing edge indefinitely, without liability of damage.

The sheet metal form of socket member shown in Figs. 11, 12 and 13 is also formed from a blank of greater thickness than the finished article, as indicated in Figs. 12 and 13 and is compressed to the desired thickness for the reasons described with reference to the style shown in Figs. 8, 9 and 10, and the same differs therefrom in that the periphery instead of being circular, corresponds to the form of the loops 15^b. The holes 16^b, and opening 19^b are generally similar to those shown in Figs. 8, 9 and 10. Thus the structure corresponds generally to that of the wire form shown in Fig. 1, and differs therefrom in being made of one piece. The advantage of this form is that the entire structure is adapted to yield when the ball 12 is entered through the ball receiving opening 19^b. The connecting portions 18^b form the bounding wall for the opening 19^b, and when these are engaged by the ball 12 they yield by a bending movement in the direction of the movement of the ball and also are thrust outwardly ra-

dially so that momentarily the loops 15^b are slightly expanded, or opened outwardly. Because of the co-operative yielding movement described every part of the material of the socket member is active, and there is no straining of any part beyond the elastic limit, so long life and continued usefulness to the full extent is insured. The rounded edge effect and the hardening feature I find to be of particular importance in the form described and shown in the said Figs. 11, 12 and 13.

In the different forms shown the active portion of the socket member consists of a single thickness of material, providing a plurality of inwardly directed radial arms the inner ends of which engage with the ball member, and which arms in engaging with and disengaging from the ball member, involving the passage of the ball through the central opening, are adapted to yield by a combination of a transverse or bending movement and an outwardly directed thrust movement, and because of the resiliency of the material to resume the normal position, substantially in a common plane, after the ball has passed the inner extremities of the said arms.

The open spaces 24 and 24^b between the arms of the loops 15 and 15^b in the styles shown in Figs. 1 and 11 permit the said arms to yield freely and serve to produce a superior yielding effect for these particular forms of socket member, the skeleton formation of these structures permitting the entire material to be active in the engaging and disengaging of the ball member.

In the sectional view shown in Fig. 14 the blank is shown in full lines, on a very much exaggerated scale, and the outline of the finished article, obtained by compressing the blank, is shown in broken lines. The parts actually shown in section are rectangular, almost square, and represent substantially the form of cross-section for the entire contour of the blank, as shown in plan view in Fig. 13, except at corners at the ends of the connecting portions of bends 18^b, where there is some slight surplusage of material. While the walls are substantially flat and the corners are square and sharp as usual with such parts formed by means of dies, actually there is a rawness and roughness to these parts, particularly after the dies have been used more or less.

By treating the blank by compression in the manner described the raw and rough effect referred to disappears and in lieu thereof there is a positive smoothness of all surfaces on all sides and a positive elimination of all sharp corners, such elimination of the roughness being due to the flowing of the metal.

I claim as my invention:—

1. The process of forming a socket mem-

130

ber for a snap fastener having a central ball receiving opening comprising providing a blank of appreciably greater thickness than the finished socket member and having a 5 central opening and a plurality of radial passage ways extending outwardly from the said opening, and compressing the said blank to the desired thickness for the said finished socket member.

10 2. The process of forming a socket member comprising providing a blank having a central hole, a plurality of lateral holes, and connecting passages interconnecting the said lateral holes and central hole, and compressing the said blank appreciably so as 15 to harden the material and provide a rounded contour for the border walls of the said holes.

3. The process of forming a socket member for a snap fastener suitable for coöperating with a ball member having a ball supported from a base by a reduced neck 20

comprising punching from sheet metal a blank in the form of an endless structure of substantially uniform cross-section at all 25 parts of the contour, the material of the said blank being of wavy form and extending by a plurality of bends back and forth between the outer side and the central portion, the portions at the middle being separated by an open space that is slightly large 30 for a fit for the said reduced neck, the said material having thickness in excess of that of the finished socket member, and compressing the said blank to the desired thickness and thereby simultaneously closing inwardly the edges of the said portions at the middle so as to appreciably reduce the dimensions of the said open space for receiving the ball member and reduced neck.

GEORGE E. PRENTICE.
